H. FINCK.

RUG.

No. 16,496.

Patented Feb. 2, 1886.

UNITED STATES PATENT OFFICE.

HENRY FINCK, OF NEW YORK, N. Y., ASSIGNOR TO JOHN BROMLEY & SONS, OF PHILADELPHIA, PENNSYLVANIA.

DESIGN FOR A RUG.

SPECIFICATION forming part of Design No. 16,496, dated February 2, 1886.

Application filed December 11, 1885. Serial No. 185,423. Term of patent 3½ years.

To all whom it may concern:

Be it known that I, HENRY FINCK, a citizen of the United States, residing at New York, in the county and State of New York, have 5 invented and produced a new and original Design for a Rug; and I do hereby declare that the photographic print accompanying this specification conveys to any one skilled in the art a clear understanding of the same, and is 10 sufficient to enable such persons to use my invention.

The leading features of my design consist in a center panel ornamented by a representation of floral figures surrounded by a narrow 15 border or molding, and a wide border in conventional florid ornamentation. At each end of the wide border is a narrow cross border or molding, and at each end of the rug is represented a narrow panel ornamented by a representation of a floral figure. The whole is surrounded by a narrow border, as shown in the photographic print accompanying this specification.

What I claim as my invention is—

The design for a rug, consisting of a center 25 panel ornamented by a representation of floral figures and surrounded by a narrow border or molding, and a wide border in conventional florid ornamentation, and at each end a narrow cross-border, and at each end a narrow 30 panel ornamented by a representation of a floral figure, the whole surrounded by a narrow border, as shown and described.
